United States Patent

Des. 236,344
Patented Aug. 19, 1975

236,344

SPRINKLER

Theodore Vorkapich, Brunswick, Ohio, assignor to
American LaFrance, Inc., Willoughby, Ohio

Filed Jan. 18, 1974, Ser. No. 434,683

Term of patent 14 years

Int. Cl. D23—01

U.S. Cl. D23—6

FIG. 1

FIG. 2

FIG. 3

FIG. 4

FIG. 5

FIG. 1 is a front elevation view of a sprinkler showing my new design;

FIG. 2 is a side elevation thereof;

FIG. 3 is a top plan view thereof;

FIG. 4 is a bottom plan view thereof; and

FIG. 5 is a rear elevation thereof.

The characteristic feature of my design reside in the configuration of the sidewall deflector as shown.

I claim:

The ornamental design for a sprinkler, as shown and described.
